UNITED STATES PATENT OFFICE.

WRIGHT D. SMITH, OF DETROIT, MICHIGAN.

ROTARY FAN-BLOWER.

SPECIFICATION forming part of Letters Patent No. 272,595, dated February 20, 1883.

Application filed October 18, 1882. (No model.)

To all whom it may concern:

Be it known that I, WRIGHT D. SMITH, of Detroit, in the county of Wayne and State of Michigan, have invented new and useful Improvements in Rotary Fan-Blowers; and I do hereby declare that the following is a full, clear, and exact description thereof, reference being had to the accompanying drawings, which form a part of this specification.

10 The nature of this invention relates to certain new and useful improvements in that class of fan-blowers which have openings for the admission of air opposite each other and in each side of the fan-case, by means of which an even discharge of air is obtained, and entirely avoiding the loss of power which occurs in blowers of this description where the inlets are opposite each other, with nothing between the openings to separate the air-currents, 20 which meet at nearly a central point, and in the operation of the fan produce an unsteady current.

25 The invention consists in providing a central disk secured to the fan-shaft, and to which the buckets or fans are secured, and which divides the inlet currents and reunites them at the discharge in a direct and steady current, and in the various combinations necessary to produce these results.

30 Figure 1 is a perspective view of the fan-shaft, disk, wings, fans, and pulleys detached from a fan-case. Fig. 2 is an elevation of the same, with the fan-case shown in section. Fig. 3 is a side elevation of the disk and fans.

35 In the accompanying drawings, which form part of this specification, A represents a disk, the diameter of which will fit the internal diameter of the fan case or scroll, within which the disk revolves. This disk is secured to the 40 shaft B, so that its position when in place is in the center of the scroll, in which there are

the usual air-inlets upon each side. Upon the opposite faces of this disk are secured the wings or fans D, which may be of any desired form, as the different surfaces to which such devices are applied may require. These fans or wings may be cast with the disk, or they may be secured thereto by bolts or studs a, and they are arranged alternately, or "staggered," with relation to each other on the two sides of the disk, as shown, D representing those upon one side, and D' those upon the opposite side. These wings are set staggering to equalize the pressure of air, because if the wings were attached opposite each other there would be a tendency to inequality in the blast. It is preferable with this construction to employ pulleys C and C'—one on each end of the shaft—although this is not essential, as the results may be produced by the employment of one pulley. This invention is designed as an improvement upon a rotary blower which was patented to me November 22, 1881, although I do not desire to confine its use to the specific construction of blower described in the said Letters Patent, as it will be found of great utility in all rotary blowers which are provided with air-inlets opposite each other in each side wall of the fan-case.

What I claim as my invention is—

In a rotary blower, in combination with the fan-case thereof, which is provided with air-inlets opposite each other in the side walls of such case, a centrally-located disk secured to the fan-shaft and provided upon each face with alternated or staggered fans or wings, substantially as and for the purposes described.

WRIGHT D. SMITH.
